UNITED STATES PATENT OFFICE.

AUGUST GOERTZ, OF NEWARK, NEW JERSEY.

LOCK FOR BAG OR SATCHEL FRAMES.

SPECIFICATION forming part of Letters Patent No. 379,158, dated March 6, 1883.

Application filed December 28, 1887. Serial No. 259,208. (No model.)

To all whom it may concern:

Be it known that I, AUGUST GOERTZ, of Newark, in the county of Essex and State of New Jersey, have invented certain new and 5 useful Improvements in Locks for Bag or Satchel Frames, of which the following is a specification.

This invention relates to an improved fastener for bag or satchel frames, which fastener 10 can be conveniently opened and closed, and which forms an ornamental locking device for said frames; and the invention consists of a fastener for bag or satchel frames, which is composed of a centrally-recessed stud attached 15 to one jaw of the frame, a spring-actuated hook that is pivoted to the recessed stud and adapted to engage a transverse bar or projection on the second jaw of the frame. The locking-hook is provided with a rounded-off 20 front edge, so as to pass readily over the transverse bar, spring action being imparted to the hook by a U-shaped spring set into a side recess of the shank of the hook, said spring being seated at one end in a socket of the base 25 of the recessed stud and at the other end in a recess at the rear end of the hook.

In the accompanying drawings, Figure 1 represents a side elevation of a bag or satchel, showing my improved fastener in end elevation. Fig. 2 is a vertical transverse section of the same on line $x-x$, Fig. 3; and Fig. 3, a top view, partly in horizontal section.

Similar letters of reference indicate corresponding parts.

35 In the drawings, a represents a centrally-recessed stud, which is riveted by its shank or base to one jaw of the bag or satchel frame. Into the recess of the stud a is pivoted a locking-hook, b , by a transverse pivot-pin, d , said 40 locking-hook being provided with a side recess, b' , in which is arranged a U-shaped spring, e , one end of which passes along the front heel, b^2 , of the side recess, b' , into a socket, e' , in the shank or base of the stud a , while 45 the other end engages a recess near the heel b^3 at the rear end of the locking-hook b , as shown clearly in Fig. 2. The shank of the locking-hook b is preferably made of disk shape, so as to fill up the recess of the stud a . The outer or 50 front edge of the locking-hook b is preferably rounded off and provided with a ball-shaped head or terminal, f , so as to facilitate the taking hold of the hook in opening or closing

the fastener. The locking-hook b engages a transverse bar or projection, g , which is supported by two studs, g' , applied to the adjoining jaw of the bag-frame, the rounded-off front edge of the hook passing along the bar g , when the bars are pushed toward each other, so as to be raised against the tension of the spring 55 until the hook has passed over the bar and engages it by the action of the spring, keeping thereby the jaws of the spring in locked position. For opening the pocket-book frame, the hook b is lifted against the tension of its 60 spring until it clears the transverse bar g , so that the jaws of the frame can be moved away from each other. The swinging motion of the locking-hook b is limited by the heels b^2 b^3 of the recess b' , in which the spring is located, 65 said heels abutting against the base of the stud a .

The catch is readily put together and forms a neat and simple fastening device for bag or satchel frames, that secures the automatic 75 locking of the jaws when they are closed, while it is readily opened by lifting the locking-hook, so as to release it from the fixed transverse bar of the second jaw.

Having thus described my invention, I claim 80 as new and desire to secure by Letters Patent—

1. The combination of a centrally-recessed stud attached to one jaw of the bag or satchel frame, a locking-hook pivoted to said stud, a spring set into a side recess of the hook 85 and secured to the shank of the stud, and a fixed bar or projection attached to the second jaw of the frame and adapted to be engaged by the hook, substantially as set forth.

2. The combination of a centrally-recessed 90 stud riveted to one jaw of the bag or satchel frame, a locking-hook pivoted to said stud and provided with a side recess, and heels at both sides of said recess, a U-shaped spring located in said recess and applied to a socket 95 in the base of the stud and to a recess of the locking-hook, and a transverse bar or projection attached to the second jaw of the frame, substantially as set forth.

In testimony that I claim the foregoing as 100 my invention I have signed my name in presence of two subscribing witnesses.

AUGUST GOERTZ.
